UNITED STATES PATENT OFFICE.

MARTIN VAN BUREN SMITH, OF NEW YORK, N. Y.

FURNACE.

No. 860,888.

Specification of Letters Patent.

Patented July 23, 1907.

Application filed June 26, 1906. Serial No. 323,483.

To all whom it may concern:

Be it known that I, MARTIN VAN BUREN SMITH, a citizen of the United States of America, and resident of the borough of Manhattan, of the city of New York, county 5 and State of New York, have invented certain new and useful Improvements in Furnaces, of which the following is a specification, reference being had to the accompanying drawings forming a part thereof.

My invention relates to improvements in furnaces, 0 and particularly to regenerator furnaces in which producer gas is adapted to be employed.

The main object of my invention is to simplify furnaces of this description, and to provide whereby a uniform heat may be obtained throughout the furnace 5 and the temperature easily regulated, whereby the furnace may be employed for the purpose of malleable- izing iron.

With these ends in view I construct a furnace with a central combustion chamber, chambers upon either 10 side thereof with checker work contained therein, and suitable channels, ducts, and controlling valves whereby air is admitted downward through the checker work in either side chamber at will, such air discharging through openings between the said side chambers and 15 the combustion chamber at the base thereof, and gas is admitted at about the point at which air enters the combustion chamber, so that the air and gas may be intimately mingled for combustion purposes in the said combustion chamber, and may finally escape through 20 the checker work in the opposite said side chamber. I so arrange the main air passages leading to each of the said side chambers that they may be used as air inlet passages and passages for the discharge of the spent products of combustion at will, and I preferably 25 provide the valve controlling means for both these two passages at the base of the stack or uptake, all as will be presently more fully set forth.

In order that my invention may be fully understood, 30 I will now proceed to describe an embodiment thereof with reference to the accompanying drawings illustrating same, and will then point out the novel features in 35 claims.

In the drawings: Figure 1 is a view in longitudinal section through the furnace, substantially upon the 40 plane of the line 1—1 of Fig. 2. Fig. 2 is a view in horizontal section therethrough substantially upon the plane of the line 2—2 of Fig. 3. Fig. 3 is a view in transverse section therethrough substantially upon the plane of the line 3—3 of Fig. 2. Fig. 4 is a detail sectional view through the base of the stack and the valve controlling mechanism for the admission of air and the discharge of products of combustion.

Referring to the drawings by reference characters, 45 50 55 60 65 70 75 80 85 90 95 100 105 110 designates the central combustion chamber, and 6, 7 the chambers upon either side thereof. These chambers contain checker work 8, and are separated from the

main combustion chamber 5 by party walls 9. Vertical passages 10 connect at their lower ends with horizontal channels 11, 12, and, at their upper ends, with cross-over passages, 13, 13 which lead into the checker 60 work of the chambers 6 and 7, respectively. The horizontal channels 11 and 12 pass round to the rear of the furnace, and connect at their ends with an uptake or stack 14. A deflecting valve 15, operated by a lever 16, opens one or other of the said passages to the said uptake or stack at will. In Fig. 4 of the drawings, it is shown as closing the channel 12 to the stack or uptake 14, and opening the channel 11 thereto. Air inlet valves 17 and 18 are arranged beneath the valve 15 at points as low as possible, the said valves arranged to 70 admit air into either of the said channels or to close admission of air thereto.

In Fig. 4 the valve 18 is shown as closed so as to prevent air from entering the channel 11, while the valve 17 is shown as open, so as to admit air to the channel 12. 75 A chain connection 19 is shown between the lever 16 and the valve 17, whereby the valve 17 may be conveniently held open, and, further, whereby the proper valve 17 or 18 will surely be opened in whichever position the deflecting valve 15 may happen to be adjusted. 80 The chain connection 19 is arranged so that it may be unhooked from connection with the valve 17 and connected instead with the valve 18 when desired.

Gas from a suitable source of supply, such as a producer, arranged at a convenient distance from the furnace, is allowed to enter a supply channel 20 with which longitudinal flues 21, 22, parallel with the channels 11 and 12, are arranged to communicate. Connection between the admission channel 20 and the flues 21 and 22 is controlled by means of saucer valves 23, 24, and gas ports 25 are provided to permit passage of gas from the flues 21 and 22 respectively to the interior of the combustion chamber 5. The point of admission is at substantially the base of the party walls 9, which divide the combustion chamber 5 from the regenerator chambers 6 and 7, the said ports being arranged opposite openings 26, which penetrate the said walls 9 at the base thereof and form the means of communication between the said regenerator chambers 6 and 7 and the said combustion chamber 5. It will be noted that although the openings 26 are at the base of the walls 9, they are just above the level at which air enters the channels at 17 or 18. By this arrangement air will flow in readily when either of the said valves 17 or 18 is opened, without the assistance of fans, blowers or the like. In using the furnace, gas is admitted through one or other of the flues 21, 22 by manipulation of the proper one of the valves 23, 24, while air is admitted to the channel 11 or 12 contiguous thereto by opening the proper one of the valves 17, 18. Assuming, for example, that the valve 17 is opened, and the deflecting valve 15 thrown over to the position shown in Fig.

4, the air valve 18 being closed; and the gas controlling saucer valve 23 opened while the other said gas valve is closed, gas will be admitted through the flue 21 and air through the channel 12. Air will pass up in the direction of the arrows shown in Fig. 3, through the cross-over passage 13, down through the checker work 8 in the chamber 7, and then through the openings 26, where it will meet the incoming gas passing out of the ports 25. The air and gas will be mixed at this point, 5 and, upon being ignited in the combustion chamber 25, will be consumed in the said chamber, the heat generated thereby being used in the said chamber 5 for the desired purposes. Products of combustion will then pass out through the openings 26 in the opposite 10 wall 9, up through the checker work 8 in the chamber 6, over the cross-over passage 13, down through the vertical passage 10, along the horizontal channel 11, and up through the uptake 14 to discharge. The spent products of combustion in passing through the 15 checker work 8 in the chamber 6, will part with a large portion of the remainder of their heat, whereby the checker work will be heated up to a high degree. After a while the conditions in the furnace may be reversed by closing the air valve 17, throwing over the 20 deflector valve 15, opening the air valve 18, closing the gas valve 23, and opening the gas valve 24. Gas will now enter through the flue 22, and air through the horizontal channel 11. Air in the channel 11 will pass up the passage 10, and down into the checker work 8 25 in the chamber 6. This checker work, having been highly heated, will impart heat to the incoming air to raise the temperature of same, so that, as air enters into the chamber 5 through the passages 26, it will be in a preheated condition, and hence in a better condition 30 to part with its oxygen for combustion purposes when mingling with the gas entering from the flue 22. The discharge products will now pass up through the checker work in the opposite chamber 7, heating up the checker work therein, so that, when the conditions are again 35 reversed and gas and air are admitted from the passages 21 and 12, the air drawn through the checker work in the said chamber 7 will be in like manner heated up.

The furnace may be operated first one way and then 40 the other, so that, as the checker work on one side is cooled by the incoming air, and the checker work on the other side of the chamber is heated by the discharge products of combustion, the reversing of the currents will again supply heat to the checker work which has 45 been cooled, and the heated checker work will give up its heat to the incoming air on the other side.

It will be noted that the currents in adjacent air and gas channels are in directions opposite to each other. This arrangement is made because the gas is introduced 50 under pressure greater than atmosphere, and the air under pressure slightly less than atmosphere. The relatively larger quantity of gas delivered at the front end of the gas channel will thus be balanced by the relatively larger quantity of air delivered at the contiguous 55 rear end of the air channel.

I have provided means for controlling the supply of gas through the individual ports 25, such means comprising a movable block 27 arranged above same, with the front face thereof beveled. This block forms, in 60 effect, a valve, which, by being moved back and forth,

may control the extent of discharge permitted through the individual ports 25, or may close such ports altogether against discharge. By means of these regulating devices, I am enabled to readily regulate the supply of gas at different points in the furnace, so as to 70 properly maintain a uniform temperature throughout. When first starting up the furnace, it is of course necessary to supply flame to ignite the combustible mixture of gas and air as it enters the furnace, and I have also found in actual practice that it is necessary to supply such flame for the first two or three times the currents are reversed. After the first two or three times there is enough heat in the furnace to cause ignition. For the purpose of supplying such flame when necessary, I have provided openings 28 in the front wall 80 of the chamber 5 about in line with the front of the party walls 9, 9. The igniting device may readily consist of a lath the length of the furnace, soaked in kerosene, lighted, and passed in through the said openings 28. This will readily ignite the gases when the gas and 85 air is admitted, and this device may be withdrawn directly ignition takes place.

In employing the furnace for malleableizing, the pots containing the material to be malleableized may be stacked up in the combustion chamber 5, a certain 90 space being left between the various pots to permit of the proper circulation of the gas, air, and products of combustion. The furnace may, of course, be used for other purposes besides that of malleableizing, yet I have found that it is peculiarly adapted for the foregoing purpose because of the even temperature which 95 may be maintained throughout.

What I claim is:

1. A furnace having a central combustion chamber and two regenerator chambers, one on each side thereof, 100 separated from the combustion chamber by party walls, through which, at the base thereof, are inlet passages, independent and unconnected air and gas channels, the former having vertical channels leading therefrom to the top of the regenerators, and the latter having discharge 105 ports leading therefrom into the combustion chamber, and opening into said chamber in front of the inlet passages, and means for controlling the air and gas inlet passages, substantially as set forth.

2. A furnace having a central combustion chamber and 110 two regenerator chambers, one on each side thereof, separated from the combustion chamber by party walls, through which, at the base thereof, are inlet passages, and independent and unconnected air and gas channels, the former having vertical channels leading therefrom to 115 the top of the regenerators, and the latter having discharge ports leading therefrom into the combustion chamber, a stack or uptake communicating with both the said air channels, a reversing valve closing one or other of the said passages to the said stack or uptake, air inlet valves 120 arranged beneath said reversing valve for admitting air to either one or other of the said inlet channels, and means for controlling the gas channels, substantially as set forth.

3. A furnace having a central combustion chamber and 125 two regenerator chambers, one on each side thereof, separated from the combustion chamber by party walls, through which, at the base thereof, are inlet passages, air and gas channels, the former having vertical channels leading therefrom to the top of the regenerators, and the 130 latter having discharge ports leading therefrom into the combustion chamber, means for controlling the said individual ports or passages, and means for controlling the air and gas inlet passages, substantially as set forth.

4. A furnace having a central combustion chamber and 135 side chambers each separated therefrom by a wall, checker work contained in said chambers, inlet passages

from said side chambers to the said combustion chamber through the base of said side walls, independent horizontal gas and air channels beneath each of said side chambers, ports or passages leading from said gas channels into said central combustion chamber, contiguous said inlet passages, vertical channels from said air channels, opening to the top of the checker work in said side chambers, a stack or uptake with which said horizontal air channels communicate, a reversing valve in said stack or uptake, air admitting valves arranged beneath said reversing valve, and gas controlling valves for the said gas channels.

5. A furnace having a combustion chamber 5 and regenerator chambers 6 7 upon either side thereof containing checker work 8, said regenerator chambers separated from said combustion chamber by party walls 9, said party walls having passages 26 at the base thereof, air inlet channels 11 and 12 and gas inlet channels 21 and 22, vertical passages 10 10 leading from said air channels 11 12, cross-over passages 13 connecting said vertical passages with the checker work in each of said chambers 6 7, a plurality of gas passages 25 leading from the channels 21 22 and discharging into the chamber 5 adjacent the openings 26 26, an uptake 14 connecting with both of said air channels 11 12, a reversing valve 15 in said uptake, air inlet valves 17 18 in the said uptake beneath the reversing valve, gas controlling valves 23 24, and individual controlling means for the gas passages 25.

6. A furnace having a central combustion chamber and two regenerator chambers, one on each side thereof, sep-

arated from the combustion chamber by party walls, through which, at the base thereof, are inlet passages, air and gas channels, the former communicating with the upper end of the regenerator chambers and arranged to be opened to atmosphere at points below the said inlet 35 passages, and the latter having discharge ports leading therefrom into the combustion chamber, substantially as set forth.

7. A furnace having a central combustion chamber, of two regenerator chambers, one on each side thereof, separated from the combustion chamber by party walls, through which, at the base thereof, are inlet passages, independent air and gas channels arranged side by side beneath the said regenerator chambers, the currents in 40 said air and gas channels arranged to pass, respectively, 45 in opposite directions therethrough, the said air channels having vertical passages leading therefrom to the top of the regenerator, and provided with means for admitting air thereto at a pressure not greater than that of atmosphere, and the said gas channels having discharge 50 ports leading therefrom into the combustion chamber at points contiguous to the points at which the said inlet passages open into the said combustion chamber, and adapted to receive and transmit gas under pressure therethrough.
